CROSS ROLLING MILL

Michael Richard Hendrickson, New Brighton, Pa., assignor, by means assignments, to Diescher Tube Mills, Inc., Beaver Falls, Pa., a corporation of Pennsylvania

Application April 15, 1942, Serial No. 439,025

11 Claims. (Cl. 80—13)

This invention relates to disc stabilizing means for cross-rolling mills of the kind in which a pair of rotary guide discs, or in some cases a single disc, engage the work-piece as it is rotated and advanced between a pair of helically acting skewed pressure rolls, commonly termed "cross-rolls." Cross-rolling mills of this kind are shown in the S. E. Diescher Patents 1,586,975, 1,870,209, 2,031,761 and 2,042,832.

The guide discs and cross-rolls of such mills are driven at a comparatively high R. P. M., and the peripheral work-engaging faces of the guide discs move at correspondingly high speed in high pressure contact with the rapidly rotating and longitudinally advancing workpiece. A more or less unsteady pressure is thus exerted on the periphery of the disc tending to cause a slight weaving, or vibratory movement, of the disc in the direction of its axis of rotation, resulting, it may be, from slight clearances between parts of the disc mounting or slight flexibility in parts of the machine or in the disc itself, or from a lack of complete rigidity in the mounting of the disc on its shaft. When the guide discs are, as they should be, set with one peripheral edge close to one of the cross-rolls, the edge of the vibrating or weaving disc may come into engagement with the cross-roll, causing damage to the work-engaging surface of the roll and to the surface and edge of the work-engaging peripheral face of the disc, resulting not only in shortening the life of these parts but also in impairing the surface finish of the product.

The object of the present invention is to provide cross-rolling mills of the kind referred to with disc stabilizing means whereby the discs are maintained with their work-engaging peripheries properly positioned, vibratory motion thereof being prevented or at least substantially reduced. To this end, there is provided according to the invention means for applying pressure to one side of each guide disc. The application of such stabilizing pressure to the side of the guide discs has greatly improved the operation of a cross-rolling tube-elongating mill of the kind referred to to which the invention has been applied, resulting in a material decrease in the amount of time lost in mill operation attributable to the wear of the disc rims and wear on the rolls, and in a superior surface finish on the product.

A full understanding of the invention can best be given by a detailed description in connection with drawings showing an illustration embodiment of the invention in the form now consid-

ered best and modifications thereof. Such a description will now be given in connection with the accompanying drawings, in which—

Fig. 1 is a partially sectioned end view, from the exit side, of a tube elongating mill provided with disc stabilizing means in accordance with the invention;

Fig. 2 is an enlarged detail plan view of the stabilizing device for the upper disc;

Fig. 3 is a section taken on line 3—3 of Fig. 2;

Fig. 4 is an enlarged sectional view taken on line 4—4 of Fig. 1;

Fig. 5 is further an enlarged diagrammatic view illustrating the direction of the force exerted on one of the guide discs by the rapidly rotating workpiece;

Fig. 6 is a view showing the upper guide disc and one of the cross-rolls and stabilizing means of an alternative form;

Fig. 7 is a detail sectional view taken on line 7—7 of Fig. 6; and

Fig. 8 is a view illustrating another form of the disc-engaging pressure shoe as applied to the stabilizing device for the upper disc.

Referring to the drawings, and first to Figs. 1 to 5, Fig. 1 shows a tube elongating mill of the kind disclosed in the S. E. Diescher Patent 1,870,209, the mill having a pair of helically acting cross-rolls 10 in the pass between which a tubular blank 11 which is being reduced is rotated and given a helical advancing movement on a mandrel 12, and a pair of peripherally grooved guide discs 15 mounted on opposite sides of the pass line with their axes extending at or about right angles to the pass line and the rims of the discs extending between the cross-rolls to engage the tubular blank. The cross-rolls are skewed, being mounted with their axes inclined to each other and to the line of feed of the blank between them, and are suitably driven. The guide discs are detachably mounted each on the end of a shaft 20 journaled in a bearing shell, or housing, 21, the shafts being driven through universal couplings 22 to rotate the discs in the direction of longitudinal movement of the blank or workpiece at a peripheral speed materially in excess of the longitudinal movement of the workpiece.

The bearing shells 21 are mounted to be longitudinally movable in vertically adjustable frames 23 and 24 respectively and are held against rotation as by a key 25, as shown for the upper shell. The shells are moved to set the guide discs with their rims in desired relationship with the cross-rolls, or for withdrawing the shells for disc

changing, by adjusting means comprising, as shown for the upper shell, a threaded end piece 30 secured to the outer end of the shell and having threaded on it a collar or sleeve 31 which carries a worm gear 32. The internally threaded sleeve 31 is rotatably mounted and held against axial movement in the frame 23 (or 24), and the worm gear is engaged by a worm 33 which is turned by means of a hand wheel 34 or otherwise. The bearing shells may thus be moved in either direction as desired.

The guide discs are spaced apart sufficiently to permit the tubular blank, under the wall-reducing pressure of the cross-rolls, to bulge somewhat away from the mandrel as described in the S. E. Diescher Patent 1,870,209, and as illustrated in Fig. 5 of the drawings thereof. The peripheries of the discs are grooved, or concavely curved transversely, for engaging the bulging wall of the blank as it comes from one of the cross-rolls and deflecting and directing it toward the other of the cross-rolls, and each disc is set with its rim closely spaced from the cross-roll which rotates the tubular blank toward the disc, as described in the S. E. Diescher Patent 1,951,348 and as more particularly referred to hereinafter.

For stabilizing the guide discs to prevent or greatly reduce the vibratory or weaving motion referred to and maintain a steady movement of the disc rims as they engage the workpiece, a stabilizing pressure member, or shoe, is provided for engaging and pressing against the side of each disc with sufficient force to hold the disc against harmful vibratory movement under the operating load. These pressure members are mounted to engage the side of the disc at a point spaced from the center thereof and, most desirably, close to the edge thereof and diametrically opposite the place of engagement of the disc with the workpiece, that is, diametrically opposite the pass between the cross-rolls, and on the side opposite the side which is toward the cross-roll which rotates the workpiece toward the disc.

As shown, the pressure member 40 for the upper disc (see Figs. 1, 2 and 3) is a block of suitable material detachably secured to a bracket 41 which is adjustably mounted on the frame 23. A horizontal arm of the bracket extends through a slideway in which it is secured in adjusted position by a plate 42 clamped against the bracket arm by means of cap screws 43. The bracket is adjusted by loosening the cap screws and moving the bracket forward to force the pressure member or shoe 40 against the side of the disc by means of screws 44 (see Fig. 2). The block 40 serving as the stabilizing shoe may be of any suitable material, such as a suitable metal or a suitable hard wood. It has been found most desirable, however, to use a block of non-metallic water-lubricated bearing material, such as Micarta or Textolite. The water lubrication may be effected in any suitable manner, as, for example, by directing a small stream of water against the side of the disc from a suitably placed nozzle 45, as indicated for the lower disc. The water thus supplied serves also for cooling the disc rims, taking the place of other water supply means as commonly provided for this purpose.

The pressure member 50 for the lower disc (see Figs. 1 and 4) is also formed by a block or shoe of suitable material, most desirably Micarta or similar material. While the upper stabilizing shoe bears against the inner side of upper disc,

that is, the side toward the bearing frame 23, the lower stabilizing shoe bears against the outer side of the disc, that is, the side away from the bearing frame 24.

As here shown, the shoe 50 is carried by an adjustable part 51 of an arm, or bracket, 52 pivotally mounted in a housing 53 which is attached to the bearing frame 24. Bracket 52 is pivoted on a pin 54 extending between side walls of the housing 53 and it is held in operative position by a removable locking pin 55. Bracket 52 has a non-cylindrical bore into which an extension 56 of the adjustable part 51 extends with a sliding fit. A screw rod 57 extends through a smooth bore of part 51 and its extension 56 with its inner threaded end in a threaded bore in the bracket 52. A head 60 on the outer end of screw rod 57 bears against part 51 so that by turning the screw rod by means of hand bars extending from the head 60, part 51 may be moved inward to bring the shoe 50 into engagement with the disc and to force the shoe against the disc to apply the desired stabilizing pressure thereto. Part 51 is locked in adjusted position by means of a latch 61 which engages a toothed ring 62 on the head 60.

When the lower disc is to be changed, the locking pin 55 is withdrawn and bracket 52 is permitted to swing downward, thereby moving the shoe 50 outward and downward away from the disc, as to the position indicated by dotted lines in Fig. 1.

As described in the S. E. Diescher Patent 1,591,348, each of the guide discs is, in the mill illustrated and for best results, set with its rim closely spaced from the cross-roll which rotates the tubular blank toward the disc, so that the disc immediately engages and deflects the metal as it is forced thereagainst by the cross-roll. The other cross-roll draws the metal away from the disc referred to and forces it against the other disc. The pressure of the bulging wall of the blank on each disc is thus predominantly against the inwardly sloping part of the peripheral face of the disc which is nearest the side of the disc facing the cross-roll which rotates toward the disc, and the portion of the peripheral face toward the other side of the disc takes little, if any, of the great pressure exerted on the disc by the bulging wall of the blank. Therefore, since, as explained in said Diescher Patent 1,870,209, the transverse friction between the discs and the rapidly rotating blank is greatly lessened by the rotation of the discs in the direction of longitudinal movement of the blank at a speed materially greater than the longitudinal movement of the blank, and because of the very high pressure exerted by the bulging blank against the pressure-receiving inwardly-sloping part of the face of the discs, the resultant of the forces acting on the rims of the discs is in the direction of the arrows A in Fig. 5, having an axial component in the direction of the cross-roll which rotates the blank toward the disc, that is, to the left in Figs. 1 and 5 on the upper disc and to the right on the lower disc.

Most desirably, therefore, the stabilizing pressure applied to each disc to counteract the thrust on the rim of the disc by the workpiece and to stop the vibratory movement of the disc, when applied at a point diametrically opposite the point of engagement with the workpiece, is applied to the opposite side of the disc from the side which

is toward the cross-roll which rotates the workpiece toward the disc, as shown in Fig. 1.

It is believed that the vibration of the discs of the mill to which the invention has been applied, which before use of the present invention caused excessive wear on the work-engaging surfaces of the discs and rolls and resulting damage to the surface of the product, was due not only to slight working clearances in and yielding of the disc mounting parts, including, it may be, the mounting of the disc on the shaft, but also to slight bending of the discs, which in a mill for reducing comparatively small tubing are of limited thickness and rigidity. However, that may be, the great value of the invention in lengthening the life of the discs and rolls and improving the quality of the product has been proved.

Figs. 6 and 7 illustrate an arrangement in which, instead of having a presser shoe mounted to engage the side of the guide disc at a point diametrically opposite the place of engagement of the disc with the workpiece, two presser shoes 90 are mounted in the main frame of the mill to engage the side of that half of the disc which is toward the workpiece and at points spaced in opposite directions from the point of engagement with the workpiece. When presser shoes so located are used, they should, most desirably, engage the side of the disc which is toward the roll which rotates the workpiece toward the disc.

While the use of presser shoes formed of a block of suitable material as described has been found in practice to be very satisfactory, frictional resistance between the shoe and the disc causing only negligible increase of the load on the disc motors, a roller type shoe, such, for example, as the presser shoe 95, shown in Fig. 8 as mounted for stabilizing the upper disc, may be used, being of any suitable construction and the roller most desirably having suitable anti-friction bearings. As shown in Fig. 8, the shoe 95 is carried by a bracket 41a adjustably mounted like the bracket 41 of Figs. 1, 2 and 3. The block type shoe is preferred because of its simplicity.

It is to be understood that the invention is not to be limited to a tube elongating mill such as illustrated and to which the foregoing description has been largely confined, but that disc stabilizing means according to the invention may be applied to other guide disc cross-rolling mills of the kind referred to, whether for operating on tubular or solid workpieces, including piercing mills for producing tubular blanks or hollows from solid cylindrical workpieces. It is to be understood further that the invention includes changes and modifications of the preloading devices within the claims.

What is claimed is:

1. In a cross-rolling mill having a pair of helically acting skewed reducing rolls and a rotary guide disc mounted on a driven shaft to bear peripherally on the workpiece between the reducing rolls, disc stabilizing means for applying stabilizing pressure to one side of the guide disc at a point spaced from the center thereof.
2. In a cross-rolling mill having a pair of helically acting skewed reducing rolls and a rotary guide disc mounted on a driven shaft to bear peripherally on the workpiece between the reducing rolls, disc stabilizing means for applying stabilizing pressure to one side of the guide disc close to the edge of the disc and on the half thereof away from the pass between the reducing rolls.
3. In a cross-rolling mill having a pair of helically acting skewed reducing rolls and a rotary guide disc mounted on a driven shaft to bear peripherally on the workpiece between the reducing rolls, disc stabilizing means for applying stabilizing pressure to one side of the guide disc close to the edge of the disc and diametrically opposite the pass between the reducing rolls.
4. In a cross-rolling mill having a pair of helically acting skewed reducing rolls and a rotary guide disc mounted on a driven shaft to bear peripherally on the workpiece between the reducing rolls, the rim of the guide disc being closely spaced from the reducing roll which rotates the workpiece toward the disc; a member mounted to engage the opposite side of the guide disc from the side which is toward the reducing roll which rotates the workpiece toward the disc and engaging the disc close to the edge thereof and diametrically opposite the pass between the reducing rolls, and means for forcing said member against the disc to apply stabilizing pressure thereto.
5. In a cross-rolling mill having a pair of helically acting skewed reducing rolls and a rotary guide disc mounted on a driven shaft to bear peripherally on the workpiece between the reducing rolls; a member mounted to engage one side of the guide disc near the edge thereof, means for supplying lubricant to enter between said member and the disc, and means for forcing said member against the disc to apply stabilizing pressure thereto.
6. In a cross-rolling mill having a pair of helically acting skewed reducing rolls and a rotary guide disc mounted on a driven shaft to bear peripherally on the workpiece between the reducing rolls; a block of water-lubricated bearing material mounted to engage one side of the guide disc near the edge thereof, means for supplying water to enter between said block and the disc, and means for forcing said block against the disc to apply stabilizing pressure thereto.
7. In a cross-rolling mill having a pair of helically acting skewed reducing rolls and a rotary guide disc mounted on a driven shaft to bear peripherally on the workpiece between the reducing rolls; a roller mounted to engage one side of the guide disc near the edge thereof, and means for forcing said roller against the disc to apply stabilizing pressure thereto.
8. In a cross-rolling mill having a pair of helically acting skewed reducing rolls, a rotary guide disc mounted on the overhanging end of a driven shaft to bear peripherally on the workpiece between the reducing rolls, a longitudinally movable housing in which said shaft is journaled, a frame in which said housing is mounted, and means for moving said housing longitudinally for adjustably positioning the guide disc with relation to the reducing rolls; a member mounted on said frame for engaging one side of the guide disc near the edge thereof, and means for forcing said member against the disc to apply stabilizing pressure thereto.
9. In a cross-rolling mill having a pair of helically acting skewed reducing rolls and a rotary guide disc mounted on a driven shaft to bear peripherally on the under side of the workpiece between the reducing rolls; a pivoted bracket mounted to extend beneath the guide disc when in raised operating position, a member for engaging the side of the guide disc close to its lower edge carried by and movable on said bracket, and means carried by said bracket for moving said member toward and from the guide disc and for

forcing said member against the guide disc to apply stabilizing pressure thereto.

10. In a cross-rolling mill having a pair of helically acting skewed reducing rolls and a pair of guide discs mounted on driven shafts on opposite sides of the reducing rolls to bear on the work-piece between the reducing rolls; disc stabilizing means for each of said guide discs comprising a member mounted to engage one side of the disc near the edge thereof, and means for forcing said member against the disc to apply stabilizing pressure thereto.

11. In a cross-rolling tube-reducing mill having a pair of helically acting skewed rolls for reducing the wall thickness of a blank on a man-

10
15
drel and a pair of rotary guide discs mounted on driven shafts on opposite sides of the reducing rolls to bear on the tubular blank between the reducing rolls, the discs being spaced apart to permit the tubular blank to bulge somewhat away from the mandrel, and each disc having its rim closely spaced from the reducing roll which rotates the tubular blank toward the disc; disc stabilizing means for each of said guide discs comprising a member mounted to engage one side of the disc near the edge thereof, and means for forcing said member against the disc to apply stabilizing pressure thereto.
